(57) CLAIM

The ornamental design for a bottle, as shown and described.

DESCRIPTION

FIG. 1 is a top front perspective view of a bottle showing our new design;

FIG. 2 is a right side view thereof, the left side being a mirror image thereof;

FIG. 3 is a top view thereof;

FIG. 4 is a bottom view thereof; and,

FIG. 5 is a bottom rear perspective view thereof.

The broken lines in the Figures show environment that forms no part of the claimed design.

1 Claim, 5 Drawing Sheets(56)
